UNITED STATES PATENT OFFICE.

ALBERT DE LA HABA AND ERASMO GARCIA, OF ANSONIA, CONNECTICUT.

ROLL FOR CANE MILLS, CRUSHERS, AND THE LIKE.

Application filed October 4, 1926. Serial No. 139,421.

This invention relates to cane pressing apparatus, such as cane mills or crushers having two or more cooperating rolls provided with circumferential grooves and ribs. In 5 the preferred form of our invention and particularly when applied to so-called preliminary crushers which usually consist of pairs of cooperating rolls placed in advance of three roll mills, the rolls may also be provided with longitudinal grooves forming 10 teeth to hook into the cane and draw it into the roll bite.

It has heretofore been suggested to use rolls having both longitudinal and circumferential grooves in such devices, and our invention relates to a particular form and arrangement of roll grooving which will increase the efficiency of the installation both 15 in the capacity or the amount of cane handled, and in the percentage of juice extracted from a given quantity of cane passing through the mill.

One object of our invention is to provide 20 a roll for cane mills arranged to obtain an improved gripping action upon the cane so as to draw it into the roll bite more effectively than is done in such devices now in use.

Another object of our invention is to provide 25 cooperating or mating rolls for cane mills or crushers, which will have an improved shredding action upon the cane stalks so as to cause the complete breaking down and tearing apart of the stalks in order that 30 the maximum amount of juice may be expressed therefrom.

A further object of the invention is to provide 35 cooperating rolls which may have the same over-all diameter, but which will have a differential surface speed between the mating teeth of the cooperating rolls, so as to obtain an increased tearing and shredding action upon the cane.

A still further object of the invention is to 40 generally improve the grooving of rolls of this character so as to increase the capacity and the effectiveness of the entire installation in which the rolls are used, and also to provide for the free escape of the expressed 45 cane juice from the rolls.

To these and other ends the invention consists in the novel features and combination of parts to be hereinafter described and claimed.

50 In the accompanying drawings:

Fig. 1 is a side elevational view of a por-

tion of a cane mill installation, embodying our invention;

Fig. 2 is a sectional view of the crushing rollers, embodying our invention; 60

Fig. 3 is a fragmentary sectional view of the rollers in the three roll mill;

Fig. 4 is a longitudinal view of the preliminary crusher, one of the rollers being shown in elevation and the other in section; 65

Fig. 5 is an enlarged fragmentary view of the crushing rolls, showing the form and arrangement of the grooves therein.

In Fig. 1 of the drawings we have shown a portion of an installation comprising a 70 preliminary crusher 10, arranged in advance of a three roll mill 11. It will be understood that if desired one or more additional crushers may be used in advance of the one shown, and likewise, any number of three 75 roll mills may be provided to follow the mill 11.

The crusher 10 includes a roll stand 12 arranged at an inclination, as is usual, so that the cane passing between the crusher 80 rolls 13 and 14 will be directed downwardly over the chute 15 to the mill. The mill comprises the usual three roll mill stand 16, in which are mounted a top roll 17, a cane roll 18, and a bagasse roll 19, the cane 85 and bagasse rolls being arranged to mesh with and cooperate with the cane roll in drawing in the cane stalks and expressing the juice therefrom.

As shown more particularly in Figs. 4 and 90 5, the crusher rolls are provided with circumferential grooves forming ribs therebetween. These grooves are not all of the same pitch as is the case with rolls now in use, but it will be noted that some are relatively deep, while others are relatively shallow, and similarly the ribs formed by some of the grooves will be larger than those formed by others. It is well understood that while large and deep grooves and ribs will 95 draw the cane into the rolls to better advantage, the smaller and shallower grooves and ribs are better adapted to divide finely and to shred the cane and more effectively express the juice therefrom. With the arrangement shown in the drawings, we obtain the advantages of both large and small grooves upon a single roll.

In the preferred form of our invention we provide a number of groups of relatively 100 shallow grooves 20, forming the ribs 21 therebetween. The number of these grooves 110

and ribs in a group, or the number of groups arranged across the length of the roll is not of particular importance in all aspects of the invention, although the present arrangement 5 wherein four of these grooves and three ribs are arranged in a group will be found to be advantageous. It will be noted that while these grooves are relatively shallow with respect to the apex of the ribs therebetween, 10 they are in reality cut relatively deeply from the surface of the roll so that the apices of the ribs lie below the outside surface of the roll.

Between these smaller grooves and ribs are 15 arranged one or more larger grooves 22, providing ribs 23 of coarser pitch than the ribs 21. The apices of the ribs 23 lie substantially at the original or outside roll surface, and while the grooves 22 are considerably deeper than the grooves 20, the bottoms of these grooves preferably lie slightly above the apices of the ribs 21. In the preferred embodiment of our invention there 20 are two of the larger ribs 23 between each 25 group of the smaller ribs 21. As the ribs 21 lie considerably below the outside roll surface a relatively long inclined tooth surface 23^a is provided between the large rib 23 and the adjacent small rib 21, which surface will 30 be of greater area than that adjacent groove 22.

The roll 14 is also provided with longitudinal grooves 24 designed to intersect the larger ribs 23 and form therewith teeth 25 35 to hook into the cane and draw it into the roll bite. For ease in manufacture, these grooves are arranged in a single helix along the length of the roll, the angle of the helix preferably being such that the end of one 40 groove is substantially in line with the beginning of the next groove so that some teeth will at all times be in engagement with the mass of cane passing therethrough. Preferably, these longitudinal grooves are not sufficiently deep to intersect the ribs 21, so that the teeth will be provided upon the larger 45 ribs only, leaving the entire surface of the smaller ribs unbroken, so that the maximum amount of juice expressing surface will be provided. Moreover, the teeth 25 will be 50 relatively large so that an effective drawing action upon the mat of cane fed to the rolls will be obtained, it being known that larger teeth hook into the cane more effectively 55 than smaller ones.

Adjacent the ends of the roll beveled or inclined surfaces 26 and 27 are provided, these surfaces being substantially of the same pitch as the sides of the larger ribs so 60 that side flanges will be formed to guide the cane away from the edge of the rolls and prevent any loss of the cane at these points.

The bottom roll 13 of the crusher is provided with grooves and ribs, which will mate 65 with those arranged in the top roll. For in-

stance, in this roll the finer grooves are arranged nearer the roll surface and while four grooves 20 and three ribs 21 are arranged in a group in the top roll, the bottom roll will be provided with four ribs 29 and 70 three grooves 30. Between these groups of small or fine ribs are arranged larger grooves 31, forming coarse ribs 32 which mate with the ribs 23 and groove 22 of the upper roll. It will be noted that in the case 75 of the bottom roll, the coarser grooves and ribs are cut in more deeply from the outside surface of the rolls so that they will properly mate with the corresponding elements 80 of the upper roll, the apex of the rib 32 being slightly below the bottom of the grooves 30. As shown in Fig. 2, the lower roll is likewise provided with longitudinal grooves 33 to provide teeth 34, these grooves being 85 shallower than the grooves 24, and are preferably only approximately as deep as the grooves 30, so that they do not intersect the coarser ribs 32. It will be apparent that while the coarser ribs in one roll, the top 90 roll as shown, are provided with teeth to hook into the cane, the finer ribs of the other roll are the toothed ribs, so that the toothed ribs of one roll cooperate with the unbroken continuous ribs of the mating roll. With this arrangement, there is no likelihood 95 of the teeth of one roll mating with the teeth of the other roll, so as to leave places where the cane will not be acted upon by co-operating surfaces.

Moreover, it will be apparent that as the 100 apices of the larger ribs in the upper roll lie substantially at the original roll surface, and those of the lower roll lie substantially below the original roll surface, there will be a differential surface speed between the co-operating ribs, although the rolls are of the same diameter and are rotated at the same speed. Likewise, there will be a differential surface speed between the smaller ribs 105 of one roll and the smaller ribs of the adjacent rolls, these ribs in one case being closer to the surface of the roll than in the other case, as clearly shown in Fig. 5. Moreover, while in the case of the large ribs 110 the top roll, as shown, will have the greater 115 surface speed, the finer ribs of this roll will have the slower surface speed so that the differential surface speed between the co-acting 120 surfaces of the two rolls will be reversed between the coarse and fine ribs.

Our improved roll grooving is applicable to the rolls of a three roll mill as well as to the rolls of preliminary crushers, and will be equally effective in such mills in increasing the extraction and capacity thereof. As 125 shown in Fig. 3 of the drawings, the top roll 17 is grooved in a manner similar to the top roll 14 of the crusher, while the cane roll 18 and bagasse roll 19 are grooved similarly 130 to the lower roll of the crusher so as to mate

with the roll 17. It will, of course, be understood that this arrangement may be reversed if desired, in both crusher and mill, and the rolls having the larger teeth 25 may be used as the lower rolls, while the rolls having the smaller teeth 34 may serve as the upper rolls.

While we have shown and described a preferred embodiment of our invention, it will be understood that the same is not limited thereto in all of its details, but is capable of modification and variation within the spirit of the invention and the scope of the appended claims.

15. What we claim is:

1. A roll for cane crushing apparatus, said roll being provided with circumferential grooves forming ribs, certain of said ribs being of greater pitch than others.
2. A roll for cane crushing apparatus having circumferential grooves forming ribs, said ribs being arranged in a plurality of series, the ribs of one series being of greater pitch than the ribs of another series.
3. A roll for cane mills or the like, having circumferential grooves forming ribs, there being a number of groups of such ribs of relatively small pitch, and other ribs of relatively large pitch lying between such groups.
4. A roll for cane mills or the like, having upon its surface a plurality of groups of ribs of relatively fine pitch separated by one or more ribs of relatively great pitch.
5. A roll for cane mills or the like, having a plurality of groups of circumferential ribs of relatively fine pitch and ribs of relatively coarse pitch lying between said groups, the apices of the finer ribs lying nearer the roll axis than those of the ribs of greater pitch.
6. A roll for cane mills or the like, having a plurality of groups of relatively fine circumferential grooves forming ribs of relatively fine pitch, and circumferential grooves forming teeth of relatively coarse pitch between said groups, the bottoms of the fine grooves lying closer to the roll axis than the bottoms of the coarse grooves.

7. In an apparatus for treating sugar cane, a roll, having a plurality of groups of circumferential ribs of relatively fine pitch and ribs of relatively coarse pitch lying between said groups, the apices of the finer ribs lying nearer the roll axis than those of the ribs of greater pitch, and a mating roll for the first named roll having ribs of both fine and coarse pitch to mate with the ribs of the first named roll, the apices of the finer ribs being at a greater distance from the roll axis than those of the coarser ribs.

8. In an apparatus for treating sugar cane, a roll having a plurality of groups of relatively fine circumferential grooves forming ribs of relatively fine pitch, and circumferential grooves forming teeth of relatively coarse pitch between said groups, the bot-

toms of the fine grooves lying closer to the roll axis than the bottoms of the coarse grooves, and a mating roll having relatively fine and relatively coarse grooves to mate with those of the first named roll, the bottoms of the relatively fine grooves being at a greater distance from the roll axis than the bottoms of the coarse grooves.

9. A roll for cane mills or the like, having two sets of circumferential ribs, one set of ribs being of relatively fine pitch and the other set being of relatively coarse pitch, and the apices of one set of ribs being farther from the roll axis than the apices of the other set.

10. In a cane mill, a pair of cooperating rolls, each of said rolls having two sets of circumferential ribs, one set being of relatively fine pitch and the other set being of relatively coarse pitch, and the apices of one set of ribs being farther from the roll axis in each case than the apices of the other set, and longitudinal grooves upon each roll, the longitudinal grooves intersecting the coarse ribs upon one roll, and the fine ribs upon the other roll.

11. A pair of mating rolls for cane mills or the like, each having a set of ribs of relatively fine pitch and a set of ribs of relatively coarse pitch, one set of ribs being at a greater distance from the roll axis than the other so as to effect a differential surface speed between the co-acting surfaces of the ribs of the two rolls when the rolls are rotated at the same speed.

12. A pair of mating rolls for cane crushing apparatus, each of said rolls having a set of ribs of relatively fine pitch, and a set of ribs of relatively coarse pitch, the ribs on one roll being at a greater distance from the roll axis than the mating ribs of the other roll, so as to effect a differential surface speed between the cooperating roll surfaces when the rolls are rotated at the same speed.

13. A roll for cane mills or the like, having a set of ribs of relatively fine pitch, and a set of ribs of relatively coarse pitch, the apices of the former being closer to the roll axis than the apices of the latter, there being ribs of relatively fine pitch at each end of the roll and said roll having inclined end flanges to guide the cane toward the roll center.

14. A roll for cane mills or the like, having a plurality of groups of ribs of relatively fine pitch, and ribs of relatively coarse pitch between said groups, the ribs of relatively fine pitch being closer to the axis of the roll than the other ribs, and there being a group of such ribs adjacent each end of the roll, and a relatively deep inclined flange at each end of the roll adjacent each end group of relatively fine ribs to guide the cane away from the roll ends.

15. A pair of rolls for cane crushing appa-

ratus, one of said rolls having a series of unbroken continuous ribs of relatively fine pitch, and a series of circumferential ribs of relatively coarse pitch provided with teeth 5 to hook into the cane, and the other roll mating with the first named roll and having a series of circumferential ribs of relatively fine pitch provided with teeth to hook into the cane, and a series of unbroken continuous ribs of relatively coarse pitch.

16. In cane crushing apparatus, a pair of mating rolls, each of said rolls having a set of grooved ribs forming teeth to hook into the cane, and a set of continuous unbroken ribs, the grooved ribs of one roll 15 mating and co-operating with the continuous unbroken ribs of the other roll.

17. In a cane crushing apparatus, a pair

of mating rolls, one of said rolls having a series of ribs of relatively fine pitch, the apices 20 of which are disposed substantially at the outside roll surface, and a series of ribs of relatively coarse pitch, the apices of which are disposed substantially below the outside roll surface, the other roll being provided 25 with ribs of both fine and coarse pitch to mate with those of the first roll, the apices of the ribs of fine pitch of the second roll lying substantially below the outside roll surface, and the apices of the ribs of coarse 30 pitch lying substantially at the outside roll surface.

In witness whereof, we have hereunto set our hands this 1st day of Oct., 1926.

ALBERT DE LA HABA.
ERASMO GARCIA.
